UNITED STATES PATENT OFFICE.

EDWIN ALEXANDER ROTHROCK, OF LEXINGTON, NORTH CAROLINA.

DESIGN FOR A WAGON-HOUND.

SPECIFICATION forming part of Design No. 32,176, dated January 30, 1900.

Application filed December 28, 1899. Serial No. 741,870. Term of patent 3½ years.

To all whom it may concern:

Be it known that I, EDWIN ALEXANDER ROTHROCK, a citizen of the United States, residing at Lexington, in the county of Davidson 5 and State of North Carolina, have invented and produced a certain new and original Design for Wagon-Hounds; and I do declare the following to be a full, clear, and exact description of the invention, such as will enable others skilled in the art to which it appertains to make and use the same.

The invention relates to a new and original design for wagon-hounds; and it consists of a 15 design of the shape and configuration shown in the accompanying drawings, of which—

Figure 1 is a top perspective view of the hound, and Fig. 2 is a bottom perspective view.

In the drawings, 1 denotes a plate approximately triangular in form and provided on its under side with an open-ended box 2, the

top of which projects upwardly and tapers forwardly upon the upper side, as shown at 3, the diverging strips 4, the forward ends of which meet the sides of the box on the under 25 side, the two parallel strips 5, arranged on the rear end of the box, and the curved flanges 6, arranged at the forward end of the triangular plate. The strips, flanges, sides, and ends of the box project downwardly 30 from the under side of the plate.

What I claim is—

The design for a wagon-hound as herein shown and described.

In testimony whereof I have hereunto set 35 my hand in presence of two subscribing witnesses.

EDWIN ALEXANDER ROTHROCK.
